NECKTIE AND TYING ARTICLE THEREFOR

Howard C. Riordan and Leo Bethke, Oak Park, Ill.

Application March 13, 1947, Serial No. 734,416

2 Claims. (Cl. 2—153)

1

The invention relates to a necktie and more particularly to a necktie that may be prepared in a ready-tied state with a knot that need not be destroyed when the tie is untied; still further, the invention relates to means, preferably in the form of an insert or plate, for conditioning a portion of the tie to provide the knot.

Many neckties of the ready-tied type have been proposed and used prior to the present invention. These ties are characterized in one way or another by a permanent knot associated with a neckband of elastic or the like; in some cases the neckband may be of the material of which the tie is made but the neckband and tie proper are not of one piece. It is an important object of the present invention to provide an improved ready-tied necktie that may be made up from a regular or standard type necktie.

Another important object of the invention is to provide an article or means in the form of a deformable insert for stiffening or conditioning a portion of the tie so that the tie is adapted to have formed therein a knot of generally tubular construction adapted slidably to receive the neckband portion of the tie in a running fit, the construction and arrangement being such that the neckband portion may be removed from the knot and reinserted therein by the wearer without in any way affecting the knot.

It is also an object of the invention to provide a necktie of the type referred to which has the advantage of being sold and purchased either as an ordinary necktie which the wearer may tie in the usual fashion or as a necktie in which the preformed knot is included, thus adapting itself to differing tastes and desires of the wearers.

Briefly and specifically the foregoing and other objects of the invention are achieved in one preferred form by the use of a deformable insert or plate, preferably of light weight sheet metal having a generally "butterfly" shape, which is sheathed within an ordinary necktie of flattened tubular construction at a point in the necktie substantially in that portion thereof wherein the larger end of the tie narrows into the neckband. The insert includes suitable tabs that are bent over with portions of the tie included, after which the insert is rolled into generally tubular form on substantially the longitudinal axis of the tie. The insert thus stiffens a portion of the tie and the tubular formation made therein provides a knot that is preferably slightly open at one side to receive the smaller end of the tie and the remaining portion of the neckband thereof in a running fit to provide an adjustable loop. The

2

arrangement is such that the smaller end and neckband portions of the tie may be inserted through the open side of the knot either edge-wise or longitudinally. The formation of the knot may be accomplished manually by either the vendor of the tie or by the purchaser thereof.

In our copending application, Serial No. 734,417, we disclose a suitable apparatus and method for readily and easily accomplishing the forming of the knot.

A complete understanding of the present invention as embodied in a preferred form thereof may be had from the following detailed description and accompanying sheets of drawings in which:

Fig. 1 is a plan view of the insert or stiffening means;

Fig. 2 is a fragmentary view of a portion of a necktie within which the insert is sheathed;

Fig. 3 is a transverse sectional view showing the relationship between the necktie and the insert, the view being taken on the line 3—3 of Fig. 2; and

Figs. 4 to 12 illustrate progressive steps in the formation of the knot and the tying of the necktie.

The present invention is designed primarily as an improvement in the standard type of necktie. However, as will be more clearly brought out, the principles of the invention are applicable in the preparing of neckties of other types and the insert or modifications thereof is suitable for the preparing of neckwear in which it is desired to form a knot. Accordingly, the present disclosure should be taken as illustrative and not limiting.

The necktie shown in the drawings includes a main body having a large end 10 and a small end 11, the latter numeral being applied in the drawings to that portion of the tie of which the smaller end is a continuation. The portion of the necktie intermediate the ends thereof includes a neckband designated generally by the numeral 12. The tie, as is conventional, is of flattened tubular construction; that is to say, the tie is preferably made from one piece of fabric, formed to the desired shape, and having opposite longitudinal portions folded over and brought together along the longitudinal axis of the tie to provide a seam indicated at 13. The seam may or may not be stitched. Also, as is usual, the necktie may include a reinforcing or stiffening fabric 14 (Fig. 3).

The stiffening means shown in Fig. 1 herein takes the form of a plate having a main body 15, preferably formed of deformable light weight

sheet metal of generally "butterfly" shape, being generally symmetrical at opposite sides of its median axis and including opposite wing portions 16 and 17. The material of which the insert or plate is composed is preferably such that the insert is easily shaped, has some resiliency, and has the ability to retain its shape against the force of ordinary wear and tear.

The wing portion 16 includes as an integral extension thereof a laterally and diagonally extending tab 18. The wing 17 includes an extension formed integral therewith to provide a tab 19. The tab 19 includes integrally therewith a secondary tab 20. The wings 16 and 17 are lightened at 21 by the removal of metal and the tab 19 is similarly lightened at 22. The opposite marginal edges of the body portion 15 of the insert are curved inwardly, the upper edge being indicated at 23 and the lower edge at 24. These two edges 23 and 24 are concavely formed as shown in Fig. 1. The formation of these edges contributes to the general appearance of the knot when formed, as will appear hereinafter.

The tabs 18 and 19 are foldable back upon the wings 16 and 17 respectively, the former being bendable or foldable along the line A and the latter being foldable along the line B (Fig. 1). The tab 20 is foldable back upon the tab 19 along the line C (also Fig. 1).

As previously stated, the insert is adaptable for use in a standard or ordinary necktie. When it is desired that a knot be formed in such tie, the insert is first sheathed within the tie. The insert is located at that portion of the tie substantially at the junction of the larger end portion 10 and the neckband 12, or at that side of the neckband toward the larger end 10 (Fig. 2). The tab 18 is toward the larger end 10 and the tabs 19 and 20 are toward the smaller end 11. The tie is preferably laid face down upon a flat surface so that the seam 13 is up (also Fig. 2). The manner of accomplishing the knot is preferably as set forth below. The first step consists in folding the tab 18 upwardly so that it extends at a right angle to the body of the insert (Fig. 4). The larger end portion of the tie is then folded back about the upstanding tab 18 so that it assumes the position shown in Fig. 5. The tab 18, with the tie portion wrapped therearound as shown in Fig. 5 is then bent completely down upon the wing 16, so that the result shown in Fig. 6 is obtained.

The sheathed tab 19 is then folded upwardly to a position in which it extends at a right angle to the body of the insert 15 (Fig. 7). The folding of the tab 19 is continued so that it lies flat upon the wing 17 (Fig. 8) with the neckband portion 12 and smaller end 11 extending from the side of the insert opposite the side from which the larger end portion 10 extends.

The sheathed tab 20 is then bent back upon the tab 19 (Fig. 9). This operation reverses a portion of the neckband 12 so that when the neckband loop is formed the seam 13 will be toward the collar of the wearer.

Next, the insert, folded as aforesaid with the tab 18 flat on the wing 16, is rolled to a generally semi-cylindrical shape as shown in Fig. 10. The other end of the insert, with the tabs 19 and 20 folded as aforesaid, is rolled inwardly to a semi-circular shape which is generally contiguous with the rolled portion formed of the sheathed wing 16 and tab 18 (Fig. 11). The result is the formation of a generally tubular construction forming a knot indicated generally by the letter K having one side thereof open as at 25, the

opening or slot being provided by the slightly spaced apart relationship between the marginal edges of the folded and rolled sheathed insert. The folding lines A and B are non-parallel and are diagonal to the longitudinal axis of the insert so that the insert, when sheathed, folded and rolled to the form shown in Fig. 11, provides a tubular construction that lies on the longitudinal axis of the necktie and that tapers slightly toward the larger end 10 of the tie. The formation accurately simulates or resembles the knot usually fashioned in a necktie by the most expert wearer.

The "tying" of the necktie is completed by the forming of the neckband loop, which step is accomplished by means of running the smaller end 11 and neckband 12 through the knot K, the construction of which is such that these portions of the tie are slidably received to provide a running fit. The slot or opening 25 may receive the neckband portion 12 edgewise therein; or, if desired, the smaller end 11 may be run longitudinally through the knot K. The formation of the knot K, including as it does the fabric of the tie, provides a frictional engagement with the neckband 12, so that the knot, when adjusted, stays in place. The tie may be "untied" merely by slipping the neckband portion 12 edgewise out of the slot 25 in the knot K or by sliding the neckband portion longitudinally through the knot K so that the loop formed thereby is large enough to slip over the head of the wearer. Or the smaller end portion may be drawn completely longitudinally through the knot. Any of these methods may be employed, according to the desires of the wearer.

It will be seen from the foregoing that the invention provides a necktie of the ready-tied type. The tie itself is of standard construction and may be used by itself without the stiffening means or insert. The only means necessary to convert an ordinary necktie to a tie that is ready-tied and permanently tied is the insert or plate which conditions or stiffens the tie for the formation of the knot therein. It has been found that the ordinary necktie, when tied and untied in the usual fashion, is subjected to considerable wear at the portion thereof used in the knot, while the other portions of the necktie remain in good condition. According to the present invention this disadvantage is eliminated.

It will be understood of course that the foregoing disclosure pertains to a preferred form of the invention and that numerous modifications and alterations may be made therein without departing from the spirit and scope of the invention as defined in the appended claims.

What is claimed is:

1. A knot-forming insert for a necktie, comprising a blank of bendable sheet material including a central elongated body portion having opposite converging edges at its ends, and integral tabs projecting substantially perpendicularly to and from respective of such edges, said tabs having a transverse width substantially less than the length of their respective associated of such edges, one of said tabs being spaced from both ends of the body portion edge with which it is associated, the other tab being generally triangular and having converging edges of which one extends substantially perpendicularly from a midportion of the body portion edge with which it is associated, the other converging edge of the triangular tab extending from the converging end of its associated body portion edge into con-

verging relation with the perpendicularly extending tab edge, and an additional tab projecting substantially perpendicularly from the perpendicular edge of the triangular tab.

2. The combination set forth in claim 1 wherein said auxiliary tab has a transverse dimension substantially less than the length of the perpendicular edge of the triangular tab from which it projects, and wherein said additional tab is spaced lengthwise of said perpendicular edge 10 from the main body portion of the blank.
